D. S. FAULKNER ET AL.
DRAWWORKS DRUM AND METHOD OF LOCKING THE
DRUMS AND FLANGE SECTIONS THEREOF
Filed Oct. 19, 1927

Fig. 1.

UNITED STATES PATENT OFFICE.

DAVID S. FAULKNER AND EDWARD TIMBS, OF LOS ANGELES, CALIFORNIA, ASSIGNEES
TO THE NATIONAL SUPPLY COMPANY OF DELAWARE, OF NEW YORK, N. Y., A COR-
PORATION OF DELAWARE.

DRAW-WORKS DRUM AND METHOD OF LOCKING THE DRUMS AND FLANGE SECTIONS
THEREOF.

Application filed October 19, 1927. Serial No. 227,136.

This invention relates to drum constructions for rotary drawworks and to the method of locking the drum and flange sections thereof, and is more particularly related to a drum 5 formed of two half sections each including a half of the drum formed integral with a flange and to the method of uniting or locking the half sections together to form a substantially integral drawworks drum. In the copending 10 application of Edward Timbs, Serial No. 194,045, filed May 25, 1927, is illustrated a two-piece drum for rotary drawworks including two half sections united at their center to provide a substantially integral draw- 15 works drum, and this invention is directed to an improvement over the drum construction shown in the said application of Edward Timbs and to the method of locking these sections together to form the improved construc- 20 tion.

An object of this invention is to provide a two-piece drum construction including two half sections which are adapted to be united together at the center of the drum by means of 25 a lock ring adapted to fit over the flanges formed on the half sections at their adjacent ends and the lock ring being welded to the half sections on the surface of the drum in order to provide a substantially integral 30 drum.

Another object of this invention is to provide a method of uniting or locking the drum and flange sections of a drum adapted for use in a rotary drawworks which includes the 35 locking of a split ring over annular flanges formed on the drum sections, and welding the locking ring to the drum sections at spaced apart annular welds.

Other objects and advantages of this in- 40 vention, it is believed, will be apparent from the following detailed description of a preferred embodiment thereof, as illustrated in the accompanying drawings.

In the drawings:

45 Figure 1 is an elevation in half vertical section of a drawworks drum embodying this invention.

Figure 2 is an end sectional view taken substantially on the line 2—2 of Figure 1.

50 Figure 3 is an enlarged fragmental sectional view illustrating the manner of locking the drum and flange sections together by means of a split ring.

In the construction of rotary drawworks drums such, for example, as are embodied in the drawworks employed in the operation of drilling wells, it is essential that the drum and flanges of the drum be united together in a manner to prevent spreading of the flanges away from the drum and also that the entire construction be rigid or firmly tied together, as these drums must support weights extending into tons and must be operated to raise and lower these weights at a relatively fast rate in order that the drill stem or casting may be quickly removed from the well and quickly set therein. These requirements make necessary the construction of the drum in a manner not only to support the weight but to prevent the spreading of the flanges of the drum away from the drum sections thereof and also that the drum as assembled is substantially rigid horizontally of the shaft upon which the same is mounted.

In the preferred embodiment of this in- 75 vention, illustrated in the accompanying drawings, 1 and 2 indicate the half sections of the drum and are each of the same construction, and include half drum sections 3 having integral flanges 4 at their opposed ends. Formed integral with each of the sections 1 and 2 are hubs 5 by means of which the drum is supported upon the shaft 6. The drum formed may be either the type which is secured to the shaft 6 by means of keys, 80 or may be of the type which is rotatably mounted upon the shaft and driven through a differential speed mechanism from the rotating shaft 6. The hubs 5 of the sections 1 and 2 may be formed either exactly the same, 85 as illustrated in the drawings, or the hub 5 on the right hand side of the drum, as illustrated in the drawings, may extend inwardly into the drum section in order to accommodate a clutch within the brake band which 90 is secured to the flange 4. Each of the sections 1 and 2 is at its adjacent end formed with an inwardly extending flange 7 which extends inwardly within the flange to a point to practically engage the shaft 6 but not pro-

viding a tight fit at this point to permit the drum section of the drawworks drum to yield somewhat at the center as the line is reeled thereon. The flanges 7 are provided with annular channels 8 and intermediate upwardly 100 extending flanges 9 at the inner edges of the 105

channels 8. A split ring 10 is provided which is formed to provide an intermediate channel 11 adapted to fit over the two adjacent flanges 9 of the sections 1 and 2 to clamp or lock 5 the said sections together. The surfaces 12, 13 and 14 of the split ring 10 are finished while the adjacent surfaces 15 and the surfaces 16 and 17 of the flanges 7 are finished in order to provide a tight fit between the split 10 ring 10 and the flanges 9. At the other points, the split ring 10 does not engage the drum and flange sections 1 and 2 but is formed smaller than the channels provided intermediate the sections 1 and 2 on the outer surface. 15 The split ring 10 may be secured to the sections 1 and 2 in any suitable or desirable manner but it is preferably united or locked to the sections 1 and 2 by welding the edges thereof, as illustrated at 18 and 19, at longitudinally spaced points on the drum construction to the sections 1 and 2 at annularly extending welds formed entirely around the sections 1 and 2. Any suitable form of welded joint may be provided between the lock ring 20 10 and sections 1 and 2 such, for example, as is illustrated by merely cutting away the edge of the section 1 to form a triangular welded joint 20 or by cutting away at an angle the lock ring 10 and grooving out the 25 section 2 to form an annular groove and a lock welded ring extending around the drum, as illustrated at 21.

The flanges 7 are provided with inwardly extending portions 22 at spaced intervals around their inner peripheries with inwardly projecting portions providing the spaced means which practically engage the shaft 6.

Having fully described our invention, it is to be understood that we do not wish to be limited to the details herein set forth, but our invention is of the full scope of the appended claims.

We claim:

1. A rotary drawworks drum having two drum and flange sections having annular flanges at their adjacent ends, a split ring mounted between said sections with the annular flanges extending into a channel formed

in said split ring, and means for securing the split ring to said drum and flange sections 50 at the surface of the drum.

2. A drum for rotary drawworks including two sections, each section including substantially one-half of the spool and having integral flanges at their opposed ends, adjacent upwardly extending annular flanges formed on the said sections, and a split ring having a channel into which said flanges are fitted for securing the drum sections together.

3. A rotary drawworks drum including two 60 half sections, the half sections providing inner adjacent upwardly extending flanges and a split ring secured to said sections and holding said sections from expanding away from one another at said flanges.

4. A rotary drawworks drum including two drum sections, a split ring having an inner annular channel, and means secured to each of said drum sections and fitted within said annular channel.

5. A drawworks drum having a pair of complementary spool sections, the ends of the spool sections being provided with adjacent upwardly extending flanges, a connecting ring mounted between said sections and securing said sections together by said flanges, and being welded to the spool sections at spaced annular welds.

6. A rotary drawworks drum having a pair of complementary drum and flange sections 80 each formed to provide substantially one-half of the drawworks drum, annular flanges formed at the inner ends of said sections and providing inwardly extending annular flanges finished at their adjacent sides, and a ring having a central channel adapted to fit over the upwardly extending annular flanges, the said upwardly extending annular flanges and said ring being finished to provide a tight fit for holding the drum and 90 flange sections together.

Signed at Torrance, California, this 7th day of October, 1927.

DAVID S. FAULKNER.
EDWARD TIMBS.
